US00D953613S

(12) **United States Design Patent** (10) Patent No.: **US D953,613 S**
Powell et al. (45) Date of Patent: **** May 31, 2022**

(54) **AEROSOL GENERATOR**

(71) Applicant: **Nicoventures Trading Limited**,
London (GB)

(72) Inventors: **David Hillary Powell**, London (GB);
Matthew Peter Tidnam, London (GB);
Alex Pearce, London (GB); **Caroline**
Jeanne Victoire Jacob, London (GB)

(73) Assignee: **Nicoventures Trading Limited**,
London (GB)

(**) Term: **15 Years**

(21) Appl. No.: **29/705,487**

(22) Filed: **Sep. 12, 2019**

(30) **Foreign Application Priority Data**

Mar. 13, 2019 (EM) 006306700

(51) LOC (13) Cl. **27-02**

(52) U.S. Cl.
